(57) **CLAIM**

The ornamental design for a 3D printer cartridge assembly, as shown and described.

DESCRIPTION

FIG. 1 illustrates an elevated front perspective view of a 3D printer cartridge assembly;

FIG. 2 illustrates an elevated posterior perspective view, thereof;

FIG. 3 illustrates a front bottom perspective view thereof;
FIG. 4 illustrates a posterior bottom perspective view thereof;

FIG. 5 illustrates a front view thereof;

FIG. 6 illustrates a posterior view thereof;

FIG. 7 illustrates a top view thereof;

FIG. 8 illustrates a bottom view thereof;

FIG. 9 illustrates a left-side view thereof;

FIG. 10 illustrates a right-side view thereof;

FIG. 11 illustrates an elevated front perspective view of the 3D printer cartridge assembly coupled to a system for printing three-dimensional objects;

FIG. 12 illustrates an elevated posterior perspective view of the 3D printer cartridge assembly coupled to a system for printing three-dimensional objects;

FIG. 13 illustrates an exploded view of FIG. 1;

FIG. 14 illustrates an elevated perspective view of a platform of the 3D printer cartridge assembly;

FIG. 15 illustrates a bottom perspective view of the platform of the 3D printer cartridge assembly;

FIG. 16 illustrates a front view of the platform of the 3D printer cartridge assembly;

FIG. 17 illustrates a posterior view of the platform of the 3D printer cartridge assembly;

FIG. 18 illustrates a top view of the platform of the 3D printer cartridge assembly;

FIG. 19 illustrates a bottom view of the platform of the 3D printer cartridge assembly;

FIG. 20 illustrates a left-side view of the platform of the 3D printer cartridge assembly;

FIG. 21 illustrates a right-side view of the platform of the 3D printer cartridge assembly;

FIG. 22 illustrates an elevated perspective view of a piston of the 3D printer cartridge assembly;

FIG. 23 illustrates a bottom perspective view of the piston of the 3D printer cartridge assembly;

FIG. 24 illustrates a front view of the piston of the 3D printer cartridge assembly;

FIG. 25 illustrates a posterior view of the piston of the 3D printer cartridge assembly;

(Continued)

FIG. 26 illustrates a top view of the piston of the 3D printer cartridge assembly;
FIG. 27 illustrates a bottom view of the piston of the 3D printer cartridge assembly;
FIG. 28 illustrates a left-side view of the piston of the 3D printer cartridge assembly;
FIG. 29 illustrates a right-side view of the piston of the 3D printer cartridge assembly;
FIG. 30 illustrates an elevated perspective view of the housing of the 3D printer cartridge assembly;
FIG. 31 illustrates a bottom perspective view of the housing of the 3D printer cartridge assembly;
FIG. 32 illustrates a front view of the housing of the 3D printer cartridge assembly;
FIG. 33 illustrates a posterior view of the housing of the 3D printer cartridge assembly;
FIG. 34 illustrates a top view of the housing of the 3D printer cartridge assembly;
FIG. 35 illustrates a bottom view of the housing of the 3D printer cartridge assembly;
FIG. 36 illustrates a left-side view of the housing of the 3D printer cartridge assembly; and,
FIG. 37 illustrates a right-side view of the housing of the 3D printer cartridge assembly.
The broken lines shown represent unclaimed subject matter and form no part of the claimed design.
